Filed Oct. 22, 1965, Ser. No. 87,801

Term of patent 14 years

(Cl. D81—18)

Fig. 1.

Fig. 2.

Fig. 3.

FIG. 1 is a top plan view of a combined fire basket and log lighter embodying my new design;

FIG. 2 is a side elevational view of the same, both sides being identical; and

FIG. 3 is an end view of the same, both ends being identical.

The dominant features of my design reside in the portions shown in full lines.

The characteristic feature of the design resides in the channel which extends longitudinally beneath the center of the fire basket.

I claim:

The ornamental design for a combined fire basket and log lighter, substantially as shown and described.
